CONDENSER FAN CONTROL FOR
REFRIGERATION SYSTEMNorman W. Woods, Brantford, Ontario, Canada, assignor
to Keeprite Products Limited, Brantford, Ontario,
Canada, a corporation of Ontario, CanadaFiled Jan. 8, 1962, Ser. No. 164,822
14 Claims. (Cl. 62—184)

This invention relates to a refrigeration system and more particularly to a means for controlling the operation of the cooling fan for an air cooled condenser of a refrigerating unit.

In refrigerating systems wherein the condenser is located outdoors and cooled by a fan, when the ambient outdoor temperature drops to a relatively low value in the winter, below freezing, for example, the pressure in the condenser may drop to such a low value that the pressure differential between the high and low sides of the system is lower than necessary to produce efficient operation.

It is therefore an object of this invention to provide a device for controlling the operation of the cooling fan for the condenser so as to insure an adequate pressure differential between the low and high sides of the system.

More specifically, the invention contemplates a clutch interposed between the motor driven shaft and the fan propeller shaft, the clutch being responsive to the pressure of the refrigerant at the condenser for coupling and uncoupling the motor and fan shafts so that when the refrigerant pressure at the condenser falls below a predetermined value, the fan propeller shaft is disconnected from the motor driven shaft. The clutch incorporates a plurality of friction discs for effecting a driving connection between the motor driven shaft and the fan propeller shaft, there being means provided for maintaining a thin film of oil between the discs so that the extent of slippage between the discs, and therefore the relative speeds of the motor driven shaft and the fan propeller shaft, vary in accordance with the force with which the discs are squeezed together.

In the drawings:

FIG. 1 is a generally diagrammatic of a refrigeration system embodying the present invention.

FIG. 2 is a view of a condenser and fan unit showing a modified form of actuating means for the clutch.

FIG. 3 is a longitudinal sectional view of the clutch.

FIG. 4 is a view along the line 4—4 in FIG. 3.

FIG. 5 is a view along the line 5—5 in FIG. 3.

FIG. 6 is a view along the line 6—6 in FIG. 3.

Referring to the drawings, and particularly FIG. 1, a conventional refrigeration system is there shown comprising a compressor 10 connected by a conduit 12 with a condenser 14. The condenser in turn is connected by means of a check valve controlled conduit 16 with a receiver 18. Receiver 18 connects with evaporator 20 through a conduit 22 in which there is arranged an expansion valve or equivalent device 24. The outlet of evaporator 20 connects with the inlet of compressor 10 by a conduit 26. A check valve controlled bypass line 28 is illustrated extending between the condenser inlet line 12 and the outlet line 16. The present invention is concerned primarily with the manner in which the condenser 14 is cooled. As illustrated, condenser 14 is enclosed within a housing 30 having a circular opening 32 therein in which is located a fan 34. Fan 34 is driven from a motor 36 through a belt drive 38 to a clutch 40. The actuation of clutch 40, as will be explained in detail hereinafter, is controlled by the pressure of the refrigerant in condenser 14. In the embodiment illustrated in FIG. 1, a conduit 42 extends between clutch 40 and condenser 14. In this arrangement, the refrigerant in condenser 14

2

actually communicates with clutch 40. In the embodiment illustrated in FIG. 2, a conduit 44 likewise extends from the clutch 40; but instead of connecting directly with condenser 14, conduit 44 has a bulb 46 at the end thereof located in housing 30 closely adjacent the condenser 14. Conduit 44 and bulb 46 may be filled with the same refrigerant used in the system or another expansible fluid if desired. In any event, bulb 46 is located in housing 30 sufficiently close to condenser 14 so that variations in the temperature of the condenser resulting from a change in pressure in the condenser will produce a change in temperature, and therefore a change in pressure, of the fluid in conduit 44 and bulb 46.

Referring to FIG. 3, the specific clutch utilized in the arrangement illustrated in FIGS. 1 and 2 is illustrated. The clutch includes a housing 48 having an open end closed by a cover plate 50 which is secured in place by screws 52. Cover plate 50 has a fitting 54 threaded thereon. The conduit 42 or 44 connects with fitting 54. On the inner side of the cover plate, there is provided a recess 56 which cooperates with a flexible diaphragm 58 to form a chamber communicating with the fluid line 42 or 44, as the case may be. Around its periphery, diaphragm 56 is supported on one side by the cover plate 50 and on the opposite side by a ring 60. The cover plate and diaphragm assembly is sealed on the end of housing 48 by means of a gasket 62. A pusher plate 64 bears against the portion of diaphragm 58 opposite the recess 56 in cover plate 52. Plate 64 has a bushing 66 thereon into which is threaded a shaft 68. Shaft 68 extends through a thrust plate 70 fixed within housing 48 and has a spring 72 in the end thereof which bears against a thrust bearing retainer 74. Bearing retainer 74 is provided with a pair of dowel pins 76 which extend through openings 78 in thrust plate 70. A compression spring 80 around shaft 68 has one end bearing against thrust plate 70 and its other end bearing against an adjusting nut 82 which is threaded on shaft 68. By threading adjusting nut 82 along shaft 68, the force with which the pusher plate 64 bears against diaphragm 58 may be adjusted.

The opposite end of housing 48 is reduced as at 84 and is fashioned with seats for bearings 86 in which a shaft 88 is journaled. The portion of shaft 88 projecting out of the reduced end 84 of housing 48 is fashioned with a keyway slot 90 for retaining a pulley 92 thereon (FIG. 1). Pulley 92 is driven through motor 36 through the belt drive 38. Within shaft 88, there is arranged a second shaft 94. Fan 34 is mounted on shaft 94. Shaft 94 is supported adjacent the outer end of shaft 88 by bearings 96 and adjacent its inner end, it is supported by bearing 98. The inner end of shaft 88 is bell-shaped so as to form a generally cylindrical cavity 100 through which the inner end of shaft 94 projects axially. A plurality of friction discs 102, 104 are alternately arranged on the inner end of shaft 94. Friction discs 104 are mounted to rotate with shaft 94 by means of a key 106. On the other hand, friction discs 102 are mounted to rotate with shaft 88 by means of a key 108. It will be noted that the keys 106 and 108 enable the clutch discs to shift axially of shaft 94 and the bell-shaped end of shaft 88. These friction discs are retained in place by means of a clutch plate 110 and a nut 112 threaded on the inner end of shaft 94. A thrust bearing 114 is located between clutch plate 110 and retainer 74.

In use, the interior of the housing 48 is filled with oil. Thus, seals are provided at 116 and 118 to prevent oil from leaking out of the housing. In accordance with this invention, it is desired to maintain at least a thin film of oil between the adjacent friction discs 102, 104. Accordingly, each of the discs 104 keyed to the inner shaft 94 are formed on opposite sides thereof with grooves 120. Grooves 120 extend in an arcuate path from the inner

to the outer periphery of these discs. Likewise, clutch plate 110 is formed with similar grooves 122. The inner end of shaft 94 is provided with a plurality of axially extending passageways 124 which extend radially to the surface thereof as at 126 along that portion of the shaft on which the friction discs 102, 104 are mounted. When shafts 88 and 94 rotate, it will be appreciated that oil from passageways 124 is directed outwardly between the successive friction discs 102, 104 through the radially extending grooves 120 to provide lubrication between discs 102, 104. These friction discs can be formed of the same material such as steel or of different materials. Friction discs 104 are preferably formed from heat treated cold rolled low carbon steel plate and friction discs 102 are preferably formed from a heat treated alloy steel such as molybdenum steel. The notches 123 at the outer periphery of discs 102 provide axial passageways along the stack of discs for the oil directed radially outwardly through grooves 120.

It will be appreciated that in some installations, fan 34 might be mounted for rotation about a vertical axis in which case clutch 40 would be mounted with its long axis extending vertically. To assist lubrication of shaft 94 for such installations, a spiral oil groove 130 is formed around shaft 94 so that it extends from bearing 98 to the portion of the shaft surrounded by bearings 96. An oil wick 132 is located between shafts 94 and 88 to facilitate such lubrication.

As explained previously, the pressure of the fluid at the fitting 54 of clutch 40 varies in accordance with the pressure of the refrigerant in the condenser. In the embodiment illustrated in FIG. 1, this is true because the conduit 42 extends directly from the condenser to fitting 54. In the embodiment illustrated in FIG. 2, the pressure of the fluid at fitting 54 varies in accordance with the pressure of the refrigerant in the condenser because the bulb 46 is located adjacent the condenser and the temperature thereof varies generally in accordance with the temperature of the condenser. In any event, when there is a rise in pressure in the condenser, there will be a rise in the pressure of the fluid in diaphragm chamber 56. The pressure of the fluid in diaphragm chamber 56, it will be noted, urges the pressure plate 64 and shaft 68 in a direction to the right as illustrated in FIG. 3, opposing the action of spring 80. The fluid pressure in chamber 56 is exerted against the stack of friction discs 102, 104 on shaft 94 so as to compress the stack and tend to establish a driving connection between the successive discs. Thus, when nut 82 is adjusted on shaft 68 to further compress spring 80, the fluid pressure required in diaphragm chamber 56 to establish a driving relation between the successive friction discs 102, 104 will be increased. Conversely, when nut 82 is adjusted on shaft 68 to relieve the compression of spring 80, a lower fluid pressure will establish a driving relation between the friction discs 102, 104 on shaft 94. The adjustment of nut 82 will be determined by the type of refrigerant used in the system and the pressures at which it is desired to effect a coupling and uncoupling of the motor driven shaft 88 and the fan propeller shaft 94.

With the arrangement illustrated and using a particular refrigerant, nut 82 can be adjusted so that at a predetermined pressure of the refrigerant in the condenser, say 110 lbs. per square inch, the fluid pressure in chamber 136 will be sufficient to partially overcome the bias of spring 80 and apply sufficient force to the stack of discs 102, 104 on shaft 94 to establish at least a slipping driving connection between shafts 88 and 94. Thus, shaft 94 on which the fan 34 is mounted will be driven at a speed somewhat less than the speed to which shaft 88 is driven by motor 36. As the pressure in the condenser rises, the differential speed between shafts 88 and 94 will diminish so that at a predetermined higher pressure, say 130 lbs. per square inch, the discs 102, 104 will be effectively locked together and the two shafts will rotate at the same

speed. By the same token, when the pressure in the condenser falls below a predetermined value, a slippage will occur between the successive friction discs 102, 104 and the speed of the fan shaft 94 will progressively diminish as the pressure in the condenser falls until a point is reached where the fan will stop or, depending upon the design of the clutch, will rotate at a minimum speed because of residual fluid or frictional drive.

The grooves 120 in the friction discs assure a constant flow of oil between the successive discs as well as a continual wiping action. This is desirable for several reasons. In the first place, a thin film of oil between these discs will prevent the discs from squealing when they rotate relative to one another. Furthermore, the provision of a thin film of oil between successive discs enables the discs to slip past one another a variable extent so that within a predetermined range of pressure change in the condenser, the speed of rotation of fan 34 varies generally in accordance with the pressure of the refrigerant

20 in the condenser.

Thus, with the arrangement disclosed herein, when the outside ambient temperature drops to a value such that the cooling action of the rotating fan on the condenser would produce too low a pressure differential between the high and low sides of the system, operation of the fan is automatically cut off until such time as the pressure in the condenser rises to a value wherein operation of the fan is desired. Likewise, it will be appreciated that in view of the fact that the degree of slippage between the adjacent friction discs 102, 104 over a predetermined range, varies generally in accordance with the change in pressure in the condenser, the fan will be driven at a variable speed in accordance with the operating conditions and requirements of the refrigeration system.

35 I claim:

1. In a refrigeration system of the type comprising a compressor, an evaporator, a condenser connected between the compressor and evaporator, a fan for directing air over the condenser, and a motor for operating said fan, the combination of a shaft driven by said motor, a separate shaft for propelling said fan, a fluid pressure operated clutch for coupling and uncoupling said shafts, a fluid line connected with said clutch for controlling the operation of the clutch and means for causing the pressure in said fluid line to vary in accordance with the variation of the pressure of the refrigerant in said condenser.

2. The combination called for in claim 1 wherein said fluid line extends to and connects with said condenser.

50 3. The combination called for in claim 1 wherein said fluid line is provided with a temperature responsive bulb disposed directly adjacent the condenser such that the temperature of said bulb and consequently, the pressure of the fluid in said fluid line is responsive to the pressure of the refrigerant in said condenser.

4. The combination called for in claim 1 wherein said clutch includes a plurality of adjacently positioned friction discs, the successive discs being connected to rotate one with the motor shaft and the other with the fan shaft, 60 means for directing the pressure of the fluid in said fluid line to squeeze the discs together whereby the degree of slippage between successive discs is responsive to the pressure in said fluid line.

5. The combination called for in claim 4 including means opposing the action of said fluid pressure on said discs, said means being adjustable to permit variation of the pressure in said fluid line necessary to effect coupling and uncoupling of said shafts.

6. The combination called for in claim 4 including means for maintaining a film of oil between said discs.

7. In a refrigeration system, a fluid pressure operated clutch for controlling the operation of a condenser cooling fan in response to the pressure of the refrigerant in the condenser comprising a housing, a motor driven shaft, a fan driving shaft, said shafts being telescoped

one within the other and journalled for rotation in the housing, said shafts projecting out of the housing at one end, one of said shafts being adapted to be motor driven and the other being adapted to rotate the condenser cooling fan, the inner shaft being journalled for rotation within the outer shaft, a plurality of adjacently positioned discs, the successive discs being connected one with the inner shaft and the next with the outer shaft, a fluid line connected with said housing, means for transferring the pressure of the fluid in said line axially against said stack of discs whereby to vary the frictional drag between the discs and means for causing the pressure in said fluid line to vary in accordance with variation in the pressure of the refrigerant in said condenser.

8. The combination called for in claim 7 wherein said housing comprises an oil reservoir and said discs are fashioned with radially extending grooves thereon for directing oil between the adjacent faces of the successive discs.

9. The combination called for in claim 7 wherein said means for transferring the pressure of the fluid in said fluid line to said stack of discs comprises a diaphragm in said housing which is adapted to flex in response to variations of the pressure in said fluid line, and a shaft extending axially between said diaphragm and said stack of discs.

10. In a refrigeration system, a fluid pressure operated clutch for controlling the operation of a condenser cooling fan in response to the pressure of the refrigerant in the condenser comprising a housing, a motor driven shaft, a fan driving shaft, said shafts being telescoped one within the other and journalled for rotation in the housing, said shafts projecting out of the housing at one end, one of said shafts being adapted to be motor driven and the other being adapted to rotate the condenser cooling fan, the inner shaft being journalled for rotation within the outer shaft, a plurality of adjacently positioned discs, the successive discs being connected one with the inner shaft and the next with the outer shaft, a fluid line connected with said housing including a flexible diaphragm forming a chamber communicating with said fluid line, a shaft extending between said diaphragm and said stack of discs, said shaft being effective to apply a force tending to squeeze the discs together in response to the pressure in said chamber, means biasing said shaft in a direction opposing the action of the diaphragm and means for causing the pressure in said fluid line to vary in accordance with variations in pressure of the refrigerant in said condenser.

5
10

11. The combination set forth in claim 10 wherein said biasing means comprising a spring, said spring having one end engaging a fixed abutment in said housing, the opposite end of the spring engaging an abutment on said shaft, said abutments being relatively adjustable axially of the shaft to vary the bias of said spring.

12. The combination set forth in claim 10 including a thrust bearing interposed between said stack of discs and the adjacent end of said shaft.

13. The combination called for in claim 10 wherein said housing comprises an oil reservoir encompassing said discs, said discs having grooves thereon extending radially from the inner to the outer peripheries of the discs for conducting oil radially between the discs.

14. In a refrigeration system, a fluid pressure operated clutch for controlling the operation of a condenser cooling fan in response to the pressure of the refrigerant in the condenser comprising a housing, a motor driven shaft, a fan driving shaft, said shafts being telescoped one within the other and journalled for rotation in the housing, said shafts projecting out of the housing at one end, one of said shafts being adapted to be motor driven and the other being adapted to rotate the condenser cooling fan, the inner end of the outer shaft being generally bell-shaped to form a cylindrical recess surrounding the inner end of the inner shaft, a stack of friction discs in said recess, said friction discs being keyed one with the inner shaft and the next successive one with the bell-shaped end of the outer shaft, a fluid pressure line extending from the condenser to said housing, a mechanism within the housing for applying the pressure of the fluid in said fluid line axially against said stack of discs and means biasing said mechanism in opposition to the action of the pressure in said fluid line, said bias means being adjustable to thereby vary the pressure in said fluid line effective to provide a driving connection between the discs.
